UNITED STATES PATENT OFFICE.

THOMAS N. RUSSELL, OF CHICAGO, ILLINOIS, ASSIGNOR TO CHICAGO-CLEVELAND CAR ROOFING COMPANY, OF CHICAGO, ILLINOIS, A CORPORATION OF ILLINOIS.

RAILWAY-CAR.

1,272,117.

Specification of Letters Patent.

Patented July 9, 1918.

Application filed January 17, 1916. Serial No. 72,495.

To all whom it may concern:

Be it known that I, THOMAS N. RUSSELL, a citizen of the United States, residing at Chicago, in the county of Cook, State of Illinois, have invented certain new and useful Improvements in Railway-Cars, of which the following is a specification, reference being had to the accompanying drawings.

My invention relates to railway cars, and it has for one of its objects the provision of a new and improved form of car end structure adapted to be applied either to a new car in the course of its construction or to an old car of either a steel frame or a wooden frame construction. It is one of the objects of my invention to provide in a structure of this type reinforcing and strengthening means for insuring proper rigidity of the end wall of the car. As is well-known in the railway car art, upon the sudden starting or stopping of a loaded car, enormous stresses are brought to bear upon the ends of the car by the shifting of the load and it is essential that the end walls be very strongly constructed and braced if the car is to be maintained for any considerable time in first class condition. To this end I have provided means for reinforcing the end-closure members in order to secure the maximum strength longitudinally of the car, such reinforcing means being shown in the form of a rib pressed in horizontal position in a sheet metal part or parts extending across the upper edge of the end-closure adapted to coöperate with ribs pressed in vertical position in the end-closure plate or plates. In the preferred construction, this reinforcing rib is pressed in a sheet metal strip extending across the outer face of the end plate outside of the end-closure plates, and having its ends turned along the sides of the car and secured to the side plates of the frame. It is another object of my invention to provide a new and improved arrangement of ladder involving a high degree of strength and rigidity. It is another object of my invention to improve railway cars in sundry details hereinafter pointed out. The preferred means by which I have accomplished my several objects are illustrated in the accompanying drawings and are hereinafter specifically described. That which I believe to be new and desire to cover by this application is set forth in the claims.

In the drawings:

Figure 1 is a perspective view showing the end of a car-body embodying my improved construction, the roof of the car being omitted;

Fig. 2 is an enlarged detail, being substantially a cross-section taken on line 2-2 of Fig. 1;

Fig. 2^a is an enlarged detail, being substantially a cross-section taken on line 2^a-2^a of Fig. 1;

Fig. 3 is an enlarged detail, being a horizontal cross-section taken on line 3-3 of Fig. 1;

Fig. 4 is an enlarged detail, being a vertical cross-section taken on line 4-4 of Fig. 1;

Figs. 5, 6 and 7 are enlarged details showing modified forms of construction corresponding to the showing of Fig. 4; and

Fig. 8 is a perspective view of a portion of a car-body, corresponding to the upper portion of the showing in Fig. 1, but illustrating a modified form of construction.

Referring to Figs. 1 to 4, in which corresponding parts are indicated by the same reference characters,—10 indicates the end sill of a car, 11 the end plate, 12 the ridge pole, 13 the purlins, 14 the side plates, 15 the side sheathing, and 16 the floor, all being arranged in a manner well understood in the car art. As is common in car structures, the end plate 11 and the horizontally-extending frame parts connected therewith are very firmly-braced relative to the end sill 10 and the horizontally-extending frame parts connected therewith. Inasmuch as this bracing means may be of any suitable type well understood in the art it is believed to be unnecessary to illustrate it herein.

17-18 indicate sheet metal end-closure plates in vertical position side by side having their adjacent edges secured together by a plurality of bolts or rivets. The plates 17-18 are provided with flanges 19 at their lower ends which are secured in position by means of bolts 20 passing through the end sill 10. Each of the plates 17-18 is provided at its outer edge with a flange 21 turned about the side of the car, being secured in position by bolts 22 passing through the siding 15 and through the corner posts of the framework (not shown).

About the upper ends of the end-closure

plates 17—18 is secured a reinforcing strip 23 provided with a strengthening rib 24 pressed in position longitudinally thereof. At its ends the strip 23 is turned about the flanges 21 and is secured by means of bolts 25 to the side plates 14 of the car. As is best shown in Fig. 2, the strengthening rib 24 is of varying depth, being of greatest depth at about the middle of the car, at 10 which point the rib itself is preferably reinforced by a bar 24' firmly secured in any suitable manner in said rib, as by bolts 24'. The reinforcing strip 23 is secured to the upper ends of the plates 17—18 by means of 15 rivets 26 and bolts 27, the bolts 27 passing also through the end plate 11 and serving to secure both the end-closure plates and the reinforcing strip 23 firmly attached to the end plate 11. A facia plate 28 is secured to the 20 end plate 11 extending downward about the upper edges of the strip 23 and the end-closure plates 17—18.

Each of the end-closure plates 17—18 is provided with a series of strengthening ribs 25 pressed therein, comprising inwardly-pressed ribs 29 and outwardly-pressed ribs 30 in alternate position whereby a corrugated surface is produced, as best shown in Fig. 3. By the provision of the vertically-extending strengthening ribs 29—30, the end-closure plates 17—18 are rendered very strong against bowing outward between their upper and lower ends. By the provision of the reinforcing strip 23 which embraces the upper ends of the end-closure plates 17—18, the upper ends of the end-closure plates 17—18 are very strongly secured in position. By the provision of the strengthening rib 24 in the reinforcing strip 23, and by reason of the attachment of the strip 23 to the end plate 11 at intervals along the strengthening rib 24, an exceedingly strong and rigid structure is provided, the horizontally-extending strengthening rib 24 45 and the vertically-extending strengthening ribs 29—30 being adapted to mutually reinforce each other against undue strain under the trying conditions of use.

By reason of securing ladder brackets 31 upon the vertically-extending ribs 30 of the end-closure plate 17, I have provided a very strong and very reliable form of ladder. The strengthening ribs 29—30 provide sufficient strength to the plate 17 as to render 55 unnecessary the use of specially-provided reinforcing strips for the ladder structure, providing thus a greater clearance between the cars and increasing to that extent the margin of safety in the use of the ladder.

60 In Fig. 5 I have shown an end sill 32 to which the end-closure plate 33 is secured by means of bolts 34 without the use of the flange 19 as provided in the structure hereinbefore described. In Fig. 6 I have shown 65 a modified form of end sill 35 to which an

end closure plate 36 is secured by means of an inturned flange 37, as illustrated in Fig. 4. In Fig. 7 I have shown a channel-iron end sill 38 with the flanges turned outward instead of inward as in Fig. 6. In Fig. 7 the end-closure plate 39 is secured in position by means of an outwardly-turned flange 40 in lieu of the inwardly-turned flange 37 of Fig. 6.

In Fig. 8, in which I have shown a modified form of structure, the parts corresponding to those shown in Figs. 1 to 4 are indicated by the same reference characters, but with the addition of an exponent *a*. In the construction here shown the reinforcing strip 23 is omitted, and strengthening ribs 41—42 are pressed in horizontal position in the upper ends of the end-closure plates 17—18. The horizontally-extending ribs 41—42 are thus enabled to coöperate with the vertically-extending ribs 29—30 so as to strengthen the end-closure plates very materially relative to the end plate 11, the rib-reinforcing bar (not shown in Fig. 8) corresponding to the bar 24' of the first-described construction being secured to the ribs 41—42 in the construction shown by means of bolts 43.

What I claim as my invention and desire to secure by Letters Patent, is—

1. In a railway car, the combination of an end plate, an end-closure plate extending downward from said end plate and having a plurality of strengthening ribs therein extending in vertical position from substantially the lower edge of the end plate, and means for bracing said end-closure plate relative to said end plate comprising a strengthening rib extending in horizontal position along said end plate and secured thereto, whereby said horizontally-extending strengthening rib and said vertically-extending strengthening ribs mutually reinforce each other.

2. In a railway car, the combination of a plurality of end-closure plates arranged side by side transversely of the car, each of said plates having a plurality of strengthening ribs therein extending in vertical position substantially from the upper edge of the plate to substantially the lower edge, and means for bracing said end-closure plate against bowing outward between its side edges longitudinally of the car, comprising a strengthening rib extending transversely of the car between the side edges of the end-closure plate near the upper edge of said end-closure plate.

3. In a railway car, the combination of a plurality of end-closure plates arranged side by side transversely of the car, each of said plates having a plurality of strengthening ribs therein extending in vertical position substantially from the upper edge of the plate to substantially the lower edge near the floor of the car, and means for bracing

said end-closure plates against bowing outward between their side edges longitudinally of the car, comprising a strengthening rib extending transversely of the car from the 5 outer side edge of one of said end-closure plates to the outer side edge of the other of said end-closure plates near the upper edge of said end-closure plates.

4. In a railway car, the combination of a 10 plurality of end-closure plates arranged side by side transversely of the car, each of said plates having a plurality of strengthening ribs, therein extending substantially from the upper edge of the plate, and means for 15 bracing said end-closure plates against bowing outward between their side edges longitudinally of the car, comprising a strengthening rib of varying depth extending transversely of the car near the upper 20 edge of said plates from the outer side edge of the plate at one side of the car to the outer side edge of the plate at the other side of the car, said rib being of the greatest depth at that portion near the middle of the car 25 transversely thereof.

5. In a railway car, the combination of an end plate, an end sill, an end-closure plate extending from said end sill to said end plate and having a plurality of strengthening 30 ribs therein extending in vertical position from substantially the lower edge of the end plate to the upper edge of the end sill, means for securing the lower end of the end-closure plate to said end sill, and means for 35 bracing said end-closure plate relative to said end plate, comprising a strengthening rib extending in horizontal position along the outer face of said end plate and secured at intervals to said end plate whereby said 40 end-closure plate is prevented from bowing outward between its side edges relative to said end plate, said horizontally-extending rib and said vertically-extending ribs being adapted to mutually reinforce each other for 45 strengthening the end structure.

6. In a railway car, the combination of two end-closure plates arranged side by side across the end of a car, each of said plates having a plurality of strengthening ribs 50 therein extending in vertical position from substantially the upper edge of the plate, and means for bracing said end-closure plates against bowing outward between their side edges longitudinally of the car, comprising a strengthening rib extending in horizontal position near the upper edge of said end-closure plates, and means for reinforcing said strengthening rib near its middle point, said reinforced horizontally-extending 55 strengthening rib and said vertically-extending strengthening ribs being adapted to mutually reinforce each other.

7. In a railway car, the combination of a 60 plurality of end-closure plates arranged side by side across the end of a car, each of

said plates having a plurality of strengthening ribs therein extending in vertical position from substantially the upper edge of the plate, and means for bracing said end-closure plates against bowing outward between their side edges longitudinally of the car, comprising a strengthening rib extending in horizontal position near the upper edge of said end-closure plates, and means for reinforcing said strengthening rib opposite the joint between said two plates, said reinforced horizontally-extending strengthening rib and said vertically-extending strengthening ribs being adapted to mutually reinforce each other. 70

8. In a railway car, the combination of two end-closure plates arranged side by side across the end of a car, each of said plates having a plurality of strengthening ribs therein extending in vertical position from substantially the upper edge of the plate, and means for bracing said end-closure plates against bowing outward between its side edges longitudinally of the car, comprising a strengthening rib of varying depth 80 extending in horizontal position near the upper edge of said end-closure plates being of greatest depth at about the middle of the car, and means for reinforcing said strengthening rib near its middle point, said reinforced horizontally-extending strengthening rib and said vertically-extending strengthening ribs being adapted to mutually reinforce each other. 95

9. In a railway car, the combination of a 100 plurality of end-closure plates arranged side by side across the end of a car, each of said plates having a plurality of strengthening ribs therein extending in vertical position from substantially the upper edge of the plate, and means for bracing said end-closure plates against bowing outward between their side edges longitudinally of the car, comprising a strengthening rib of varying 105 depth extending in horizontal position near the upper edge of said end-closure plates being of greatest depth at the joint between said two plates, and means for reinforcing said strengthening rib opposite the joint between said two plates, said reinforced horizontally-extending strengthening rib and said vertically-extending strengthening ribs being adapted to mutually reinforce each other. 110

10. In a railway car, the combination of 120 a plurality of end-closure plates arranged side by side, a reinforcing strip extending across the outer faces of said end-closure plates at their upper ends, and means for securing the ends of said strip to the sides 125 of the car, said reinforcing strip being provided with a horizontally-extending strengthening rib of varying depth increasing toward the middle of the car, and said end-closure plates being provided with ver- 130

tical ribs extending downward from said reinforcing strip, said horizontal rib and said vertical ribs being adapted to mutually reinforce each other for bracing the end-closure plates against bowing outward longitudinally of the car.

11. In a railway car, the combination of an end plate, a plurality of end-closure plates arranged side by side and bearing at their upper ends on the outer face of the end plate, each of said end-closure plates being provided with a plurality of strengthening ribs therein extending in vertical position

from substantially the lower edge of the end plate, a reinforcing strip extending across the outer faces of said end-closure plates at their upper ends and provided with a strengthening rib pressed therein longitudinally thereof, and means for securing both said end-closure plates and said strip to said end plate, said horizontally-extending rib and said vertically-extending ribs being adapted to mutually reinforce each other for strengthening the end structure against strains longitudinally of the car. 15 20

THOMAS N. RUSSELL.
